UNITED STATES PATENT OFFICE.

WILLIAM J. ADLER, OF ATLANTIC CITY, NEW JERSEY.

DESIGN FOR A WATCH-FOB.

SPECIFICATION forming part of Design No. 36,136, dated November 11, 1902.

Application filed August 9, 1902. Serial No. 119,143. Term of patent 7 years.

To all whom it may concern:

Be it known that I, WILLIAM J. ADLER, a citizen of the United States, residing at Atlantic City, in the county of Atlantic and State of New Jersey, have invented and produced a new and original and ornamental Design for Watch-Fobs, of which the following is a specification, reference being had to the accompanying drawings, forming part thereof.

10 Figure 1 is a plan view of a watch-fob, showing my new design; and Fig. 2 is an edge view of the same.

As shown in the drawings, the leading or material feature of my watch-fob consists of

15 an elk's head A in relief, arranged about midway of the length of the fob B, having spreading antlers C extending upward and outward, with the outer prongs C' embracing the edges of the fob, and having a clock-face supported

20 by inner prongs C² directly above the head

A. The clock-face bears the usual hour-designations and has the long or minute hand D pointing to "XII" and the short or hour hand E pointing to "XI."

The fob B has at its upper end the cross-bar B' and chain B², with the spring-hook B³, and at its lower end it has the cross-bar B⁴ and the ring B⁵.

Having described my invention, what I claim as new, and desire to secure by Letters Patent, is—

The ornamental design for a watch-fob, as herein shown and described.

In testimony whereof I have signed my name to this specification in the presence of two subscribing witnesses.

WILLIAM J. ADLER.
